IMPROVEMENT IN TRUNKS.

SAMUEL W. VALENTINE, OF BRISTOL, CONNECTICUT.

Letters Patent No. 60,288, dated December 4, 1866.

SPECIFICATION.

TO ALL PERSONS TO WHOM THESE PRESENTS SHALL COME:

Be it known that I, SAMUEL W. VALENTINE, of Bristol, of the county of Hartford, and State of Connecticut, have made a new and useful invention or Cachet, having reference to the sealing of trunks or packages; and do hereby declare the same to be fully described in the following specification, and represented in the accompanying drawings.

In carrying out my invention I employ a strap of leather, or other suitable material, which is shown at A, in the said drawings, such strap, at or near one end of it, being securely fastened to the lid or other proper part of the trunk, bag, or parcel to be sealed. The said strap is next to be run through a loop, B, properly secured to the body or other suitable part of the trunk, bag, or parcel, the whole being so that the two parts to which the said strip and loop are attached, cannot be opened or drawn apart without the strap being extracted from the loop. A small rivet or metallic eyelet, C, is next to be inserted through the loop and the strap, and clinched or set down thereupon by a punch or other suitable means. Instead of arranging the eyelet in the loop and the strap in manner as represented in fig. 1, there may be another strap, D, affixed to the body of the trunk, and to lap on or under the strap A, in which case the eyelet may be inserted in the two straps, the same being as exhibited in fig. 2. The trunk or package cannot, therefore, be opened without either cutting one of the straps or the loop, or disarranging the eyelet, which, when done, will be proof that it has been effected designedly.

By my invention the contents of the trunk or package will be so sealed that they cannot be tampered with while the said trunk or package may be in store or in transitu.

Figures 4 and 5 represent the application of the invention, as shown in figs. 1 and 2, to a trunk or box, d, in such figures exhibiting the lid, and e the body of such article.

I do not restrict my invention to the particular form or forms in which it is represented.

I make no claim to sealing a trunk or parcel by bending a cord around it and sealing or "plumbing" such cord by a clasp or button of lead pressed upon it. Nor do I claim the employment of an eyelet or a rivet for connecting two pieces of any material together; but what I do claim as my invention or new or improved manufacture, is a trunk as made with a sealing strap, A, and loop, B, to be combined or connected by an eyelet, C, or a rivet, substantially as and for the purpose specified.

SAML. W. VALENTINE.
